(57) **CLAIM**

(22) Filed: **Mar. 29, 1999**

The ornamental design for a cover for an apparatus for generating radioactive isotopes, as shown.

(30) **Foreign Application Priority Data**

DESCRIPTION

Sep. 29, 1998 (SE) 98-1915

FIG. 1 is a top perspective view of a cover for an apparatus for generating radioactive isotopes, showing our new design;

(51) **LOC (7) Cl.** **24-01**

FIG. 2 is a top plan view thereof;

(52) **U.S. Cl.** **D24/158**

FIG. 3 is a front view thereof;

(58) **Field of Search** D24/158; 250/363.01,

FIG. 4 is a side view thereof;

250/363.02, 363.03, 363.04, 363.05, 363.08;

FIG. 5 is a side view thereof, opposite that shown in FIG. 4; and,

D15/79, 81, 85, 88

FIG. 6 is a top plan view thereof, with the doors in open position.
